UNITED STATES PATENT OFFICE

104,215

DESIGN FOR AN ELECTRIC SWITCH HANDLE OR THE LIKE

John L. Hawkinson, Hartford, Conn., assignor to
The Arrow-Hart & Hegeman Electric Company,
Hartford, Conn., a corporation of Connecticut

Application February 11, 1937, Serial No. 67,597

Term of patent 7 years

To all whom it may concern:

Be it known that I, John L. Hawkinson, a citizen
of the United States of America, residing at Hartford,
Connecticut, have invented a new, original,
and ornamental Design for an Electric Switch
Handle or the like, of which the following is a
specification, reference being had to the accompanying
drawing, forming part thereof.

Fig. 1 is a plan view of an electric switch operating
handle embodying my new design;

Fig. 2 is a side elevational view of the handle
shown in Figure 1;

Fig. 3 is an end view of the handle shown in
Figure 1.

I claim:

The ornamental design for an electric switch
handle or the like, as shown.

JOHN L. HAWKINSON.
